UNITED STATES PATENT OFFICE.

FRANK L. BOWMAN, OF MORGANTOWN, WEST VIRGINIA.

PENHOLDER.

Application filed March 23, 1921. Serial No. 454,691.

To all whom it may concern:

Be it known that I, FRANK L. BOWMAN, a citizen of the United States, residing at Morgantown, in the county of Monongalia and State of West Virginia, have invented a new and useful Penholder, of which the following is a specification.

This invention is a pen holder having means for releasing pen points from engagement therewith.

One of the objects of the invention is to provide a simple and inexpensive device, by means of which the pen point may be readily disengaged from the pen holder, no matter how badly it may have become corroded by the ink. A further object is to provide a device of the character mentioned which will prevent accidental disengagement of the pen and pen holder while in use. A further object is to provide a pen holder, having a releasing device in which there are no protruding parts to interfere with its normal use.

The invention will be hereinafter fully set forth and particularly pointed out in the claims.

In the accompanying drawing:—

Figure 1 is a side elevation illustrating a pen holder with the invention applied thereto. Figure 3 is a sectional view on the line 3—3, Figure 1, illustrating the positions of parts when the pen holder is in use. Figure 4 is a similar view illustrating the positions of the parts when the pen point is to be released. Figure 2 is a detail view illustrating the pen holder with the releasing sleeve removed.

Referring to the drawing, 10 designates the body of the pen holder, which may be of any preferred length or shape, the same being provided at one end with a spindle 12, which is offset with respect to the axis of the body 10. Rotatably mounted upon the spindle 12 is a releasing sleeve 13, having a slot 14 extending inwardly from one end, said slot being of the approximate width of the shank of a standard pen point, conventionally illustrated at 15. It will be noted that the spindle 12 is provided with a recess 16, of approximate size and shape to accommodate the shank of the pen point.

In practice the sleeve 13 and the spindle 12, are so proportioned that the recess 16 may be brought approximately to the center of the pen holder, as illustrated in Figure 3, so that the pen point may be inserted there-

in in the usual manner. When it is desired to remove the pen point, the sleeve 13 and spindle 12 are relatively rotated, so as to bring the slot 14 in register with the recess 16, as illustrated in Figure 4, whereupon the shank of the pen will fall through the slot 14. The recess 16 is of such shape that it will prevent relative rotation of the pen point 15, and the spindle 12, during the relative rotation of the spindle 12 and sleeve 13. This arrangement also prevents the pen point from interfering with the relative rotation of said sleeve and spindle, thereby insuring a smooth and uninterrupted movement of said parts. When the recess 16 comes into register with the slot 14, ample clearance is provided for the shank of the pen, and the latter may be quickly removed from the pen holder, no matter how badly the parts may have become corroded by the ink. It will be particularly noted that the shank of the pen point, interposed between the spindle 12 and the sleeve 13, creates sufficient friction to prevent accidental rotation of the sleeve upon the spindle, thereby insuring that the pen will be retained in place while the pen holder is in use. The sleeve 13 is approximately of the same external diameter as that of the body 10, so that there are no projecting parts likely to interfere with the normal use of the pen holder.

Having thus explained the nature of the invention and described an operative manner of constructing and using the same, although without attempting to set forth all of the forms in which it may be made, or all of the forms of its use, what is claimed is:—

1. A pen holder comprising a body portion provided with a spindle at one end, a rotatable sleeve eccentrically mounted on said spindle and having a slot at one end exposing a portion of the spindle, and means for preventing relative rotation of the spindle and a pen point during such relative rotation of the sleeve and spindle, as is necessary to bring said slot into register with the shank of the pen point.

2. A pen holder comprising a body portion provided with a spindle at one end, and a rotatable sleeve eccentrically mounted on said spindle and having a slot at one end exposing a portion of the spindle, said spindle having a longitudinal recess to receive the shank of a pen point, whereby rela-

- tive rotation of the spindle and the pen point is prevented during relative rotation of the sleeve and spindle, as said slot is brought into register with the said recess.
5. 3. A pen holder comprising a body portion provided with a spindle at one end arranged eccentrically with respect to the axis of the handle, a sleeve rotatably and eccentrically mounted on said spindle and having 10 a slot at one end exposing a portion of the spindle, and means for preventing relative rotation of the spindle and a pen point during relative rotation of the sleeve and spindle, as said slot is brought into register with 15 the shank of the pen point.
4. A pen holder comprising a body por-

tion provided with a spindle at one end arranged eccentrically with respect to the axis of said body, and a sleeve rotatably and eccentrically mounted on said spindle and 20 having a slot at one end exposing a portion of the spindle, the free end of said spindle having a longitudinal recess to receive the shank of a pen point, whereby relative rotation of the spindle and the pen point is prevented during relative rotation of the sleeve and spindle, as said slot is brought into register with said recess.

In testimony whereof I have hereunto set my hand.

FRANK L. BOWMAN.
